UNITED STATES PATENT OFFICE

PHILIP A. BOWEN, OF LYNN, MASSACHUSETTS, ASSIGNOR TO LILLIAN A. LITTLE, OF LYNN, MASSACHUSETTS.

SHOE-TREE.

1,119,744.

Specification of Letters Patent.

Patented Dec. 1, 1914.

Application filed August 14, 1913. Serial No. 784,724.

To all whom it may concern:

Be it known that I, PHILIP A. BOWEN, a citizen of the United States, residing at Lynn, county of Essex, State of Massachusetts, have invented an Improvement in Shoe-Trees, of which the following description, in connection with the accompanying drawing, is a specification, like characters on the drawing representing like parts.

10 This invention relates to shoe trees and it has for its object to provide a simple shoe tree which can be inexpensively manufactured and which is constructed so that it can be used equally well in shoes of different sizes.

15 I will first describe a selected embodiment of my invention which discloses the principle thereof and will then point out the novel features of the invention in the appended claims.

20 Figure 1 is a longitudinal section through a shoe tree embodying my invention showing the tree inserted in a shoe, the shoe being shown in dotted lines; Fig. 2 is a bottom 25 plan view of the toe portion of the shoe tree with a part thereof broken out; Fig. 3 is a section on the line $\alpha-\alpha$, Fig. 2.

25 In order to make a shoe tree which can be used equally well in a large variety of sizes I make the shoe tree with a toe portion 1 of resilient sheet material such for instance, as stiff leather or leather-board which will yield more or less but will tend to retain naturally its original shape. This 30 toe portion 1 is preferably made of a shape to conform to the inside of the shoe upper and it presents a top and two sides but no bottom. Coöoperating with the toe portion 35 is a resilient spreading member which tends normally to force the sides of the toe portion 40 outwardly but which member will yield inwardly to permit the device to be inserted into a narrow shoe. This resilient spreading member is herein shown as a spring device 45 presenting two arms 2 which extend longitudinally of the sides of the toe portion and bear against the inner faces thereof, said arms being made of resilient spring wire. In order to cause the toe portion to 50 fit tightly against the shoe upper I also associate therewith a spring member 3 which is adapted to engage the sole of the shoe and which yieldingly holds the toe member 1 against the inner face of the top of the shoe 55 upper. The yielding qualities of the spring

3 and the spreading member 2 as well as the yielding qualities of the toe portion 1 provide a device which can be inserted into shoes of various widths and sizes and which will yield or change its shape to fit the 60 contour of the shoes of various shapes and sizes.

65 In the embodiment herein illustrated the toe portion 1 is secured to a head 4 provided with two ears 5 between which is pivoted at 70 a tubular stem 6. This stem is provided with an extension 8 which telescopes into the stem and which is provided at its outer end with a foot portion 9 adapted to rest against the heel of the shoe. This foot portion 9 is preferably pivoted to the extension 8 at 75 10 so that it may be swung into different angular positions and it is provided with a handle 11 by which the device may be manipulated. Situated within the tubular 80 stem 6 is a spring 12 which bears at one end against the pivotal pin 7 and at the other end against the extension 8.

85 The tubular stem 6 is provided with an interior collar 14 which can conveniently be 90 made by spinning the metal of the tubular member inwardly which collar forms a stop to limit the expansive movement of the extension 8. In the embodiment of the invention illustrated, I will preferably secure 95 the spreading member and the spring 3 to the head 4 although this is not essential.

95 In the construction herein illustrated, the spring 3 is made from a length of spring wire bent to form the triangular shaped 100 portion 15 which rests against the sole of the shoe, and having its ends 16 underlying and secured to the head 4 by any suitable means as by means of solder. The ends 16 are provided with the coils or turns 17 105 which allow the spring 3 to have a movement toward and from the head but which at the same time afford a yielding resistance to the movement of the spring toward the head. I also have shown the spreading member as supported by the spring member 3 and this is done by passing the arms 2 of the spreading member through the coils 17 of the spring member; and in order to make the spreading member resili- 110 ent, I preferably form the wire from which it is made into the coil 18 between the coils 17. This coil 18 co-acts with the coils 17 to hold the spreading member in its proper position.

The extensibility of the stem 6 provides for using the shoe tree in shoes of different lengths and the construction of the toe portion with its spreading member and spring 5 3 provide for using the shoe tree in shoes of different widths. The toe member will conform to the shape of any shoe in which it is inserted and will hold the shoe smooth and free from wrinkles. Moreover the device is very simple and inexpensive to manufacture and does not require any adjustment of the parts to make it fit shoes of different sizes.

I have herein shown the sides of the toe portion as formed with inwardly-directed lips 19 at their lower edges. These lips 19 serve to hold the arms 2 of the spreading member in their proper position and prevent them from slipping down below the edges of the toe member when the tree is in use.

The spring 3 operates to force the toe member 1 upwardly against the top of the shoe upper and I have, therefore, referred 25 to this spring as an "upwardly-pressing" spring. The spreading member 2 tends normally to force the sides of the toe member outwardly and I have, therefore, referred to the spreading member as a "laterally 30 pressing" spring.

While I have illustrated in the drawings a selected embodiment of my invention, I do not wish to be limited to the constructional features shown.

Having fully described my invention what I claim as new and desire to secure by Letters Patent is:

1. In a shoe tree, the combination with a one piece toe portion of flexible sheet material, of a resilient spreading member engag-

ing the inner sides of said toe portion at or near the lower edges thereof to hold said sides yieldingly against the sides of the shoe upper and a separate upwardly-pressing spring secured to the toe portion and adapted to engage the sole of the shoe and yieldingly hold the top of the toe portion against the shoe upper. 45

2. In a shoe tree, the combination with a toe portion of flexible sheet material and presenting a top and two sides, of an upwardly-pressing spring carried by the toe portion and adapted to engage the sole of a shoe thereby to yieldingly force the top of the toe portion against the shoe upper 55 and a separate laterally-pressing spring held in place by the upwardly pressing spring and engaging the sides of the toe portion and forcing them yieldingly against the sides of the shoe upper. 60

3. In a shoe tree, the combination with a toe portion of flexible sheet material and presenting a top and two sides, of an upwardly-pressing spring carried by the toe portion and adapted to engage the sole of a shoe thereby to yieldingly force the top of the toe portion against the shoe upper and a laterally-pressing spring carried by the upwardly-pressing spring and engaging the sides of the toe portion and forcing them 70 yieldingly against the sides of the shoe upper.

In testimony whereof, I have signed my name to this specification, in the presence of two subscribing witnesses.

PHILIP A. BOWEN.
